EX

OR D 9,966

Design No. 9,966, dated May 8, 1877

UNITED STATES PATENT OFFICE

JAMES MORGAN, OF BROOKLYN, N. Y.

DESIGN FOR A MONUMENT.

Specification forming part of Design No. 9,966, dated May 8, 1877; application filed April 27, 1877.
[Term of Patent 7 years.]

To all whom it may concern:

Be it known that I, JAMES MORGAN, of Brooklyn, county of Kings, and State of New York, have invented a Design for a Monument, of which the following is a specification:

The nature of my design is fully shown in the accompanying drawing, to which reference is made.

The design relates to grave-monuments; and consists of a step-shaped base, a plain trunk, and an enlarged capital with pyramidal top part and crowning vase.

In the drawing, A represents the base, consisting of a large step, a tapering portion, b, step d, of smaller size, larger inclined step e, and small straight top e', on which the slightly tapering middle or trunk section B is placed. The capital C extends from the trunk by a groove, f, concave molding f', and step f'', on which the square base portion g of the capital rests, the same being ornamented in

suitable manner. From the square base g of the capital rises a pyramidal top part, D, having outwardly-projecting steps h, and a crowning vase, D', with side ribs h' surmounting the same.

Having thus described my invention, I claim as new and desire to secure by Letters Patent—

1. The design for a monument, consisting of a base-section, A, middle trunk-section B, enlarged capital C, pyramidal and step-shaped top part D, and surmounting vase D', substantially as shown and described.

2. The design for a capital for monuments, composed of a base portion, g, pyramidal tapering top part D, with steps b, and of a crowning vase, D', with side ribs h', substantially as described and shown.

JAMES MORGAN.
